(57) **CLAIM**

We claim the ornamental design for a wand vacuum, as
shown and described.

DESCRIPTION

FIG. 1 is a top, right perspective view of a wand vacuum
showing our new design;

FIG. 2 is a top, front, right perspective view thereof;

FIG. 3 is a bottom, back, left perspective view thereof;

FIG. 4 is a bottom, front, right perspective view thereof;

FIG. 5 is a top, left perspective view thereof;

FIG. 6 is a top, front, left perspective view thereof;

FIG. 7 is a bottom, back, right perspective view thereof;

FIG. 8 is a bottom, front left perspective view thereof;

FIG. 9 is a top view thereof;

FIG. 10 is a bottom view thereof;

FIG. 11 is a right view thereof;

FIG. 12 is a left view thereof;

FIG. 13 is a back view thereof; and

FIG. 14 is a front view thereof;

FIG. 15 is a top, right perspective view thereof with the dust
bin in an open position;

FIG. 16 is a top, front, right perspective view thereof;

FIG. 17 is a bottom, back, left perspective view thereof;

FIG. 18 is a bottom, front, right perspective view thereof;

FIG. 19 is a top, left perspective view thereof;

FIG. 20 is a top, front, left perspective view thereof;

FIG. 21 is a bottom, back, right perspective view thereof;

FIG. 22 is a bottom, front left perspective view thereof;

FIG. 23 is a top view thereof;

FIG. 24 is a bottom view thereof;

FIG. 25 is a right view thereof;

FIG. 26 is a left view thereof;

FIG. 27 is a back view thereof; and,

FIG. 28 is a front view thereof.
